UNITED STATES PATENT OFFICE.

CHARLES J. HARRIS, OF HARTFORD, MICHIGAN, ASSIGNOR OF ONE-HALF TO CHARLES M. DUNCOMBE, OF HARTFORD, MICHIGAN.

PIPE WRENCH.

Application filed May 24, 1926. Serial No. 111,294.

This invention relates to improvements in pivoted jaw pipe wrenches.

The objects of the invention are

First, to provide an improved construction 5 of pivoted outer jaw.

Second, to provide an improved adjustable connection for such a jaw to the fixed inner jaw.

Third, to provide improved retaining 10 means for the jaw.

Fourth, to provide an improved construction in which the pivoted jaw can be reversed.

Objects relating to details and economies 15 of construction and operation of my invention will definitely appear from the detailed description to follow.

The invention is clearly defined and pointed 20 out in the claims.

A structure which is a preferred embodiment 25 of my invention is illustrated in the accompanying drawing, forming a part of this application, in which:

Fig. 1 is a side elevation view of my improved wrench showing the pivoted jaw in 30 the second adjusting position, portions being indicated by dotted lines.

Fig. 2 is a similar elevation view showing the pivoted jaw swung into engagement, a 35 portion of the main part of the wrench being in section and the adjustment of the retainer and the pipe being shown by dotted lines.

Fig. 3 is an edge elevation view from the 40 right hand side of Figs. 1 and 2 showing details.

Fig. 4 is a side elevation view of the upper part of the wrench with the pivoted 45 jaw reversed and in the first or lowest position.

Fig. 5 is a detail transverse sectional view on line 5-5 of Fig. 2, with the jaw pivot indicated in full line, showing the projecting lugs 50 on the jaw head.

The parts will be identified by their numerals of reference which are the same in all 55 the views.

1 is the wrench handle formed flat and integral with the fixed jaw head 2 which is 60 suitably serrated at 21. This jaw head extends laterally and is notched on the under side at 22 with a series of notches for the adjustment of the pivoted jaw into different spaced relations. Projecting lugs 23 are at

the laterally projecting end of the jaw head 55 2 for engagement with the pivoted jaw in its disengaged position to hold the same in position ready for use. These projecting lugs 23 are seen in elevation in all the first four figures and in section in Fig. 5.

3 is the pivoted jaw slotted at 30 centrally and longitudinally to form the side pieces 31, 31—see Fig. 3. It has an integral pivot cross bar 32 constituting the pivot of the jaw which engages the notches 22 successively in 60 the different positions for purposes of adjustment. The spring bar 4 yields sufficiently to permit adjustment from notch to notch without disengaging the spring. This jaw is retained adjustably in place by the 65 spring rod 4, the upper end of which is suitably pivoted at 41 in the outer end of the fixed jaw head 2. A notched projection 11 is on the back side of the handle to receive 70 the free end 42 of the spring bar 4 which 75 snaps to place.

To assemble the wrench the spring 4 is thrown out of engagement at 42 and the handle 1 is inserted through the aperture 30 of the pivoted jaw and the jaw put in position as indicated in the various figures and snapping the bar 4 to place. The spring bar 80 4 yields sufficiently to permit adjustment from notch to notch without disengaging the 85 spring.

By removing the jaw and reversing it into the position indicated in Fig. 4, a wrench for still smaller work is produced so that with this simple construction a wrench of very 90 large capacity is produced having practically four different adjustments, each of wide capacity.

The structure is such that it can be all drop forged and consequently there are no 95 pivots or rivets or movable parts to be driven into any part. The structure is a complete assembled structure with the exception of the spring retaining bar 4 which has no work to do except to retain the pivoted jaw in place until it engages its work.

From what I have described it is clear 100 that the structure is capable of considerable modification without departing from my invention. It is not necessary that the structure be an adjustable structure in order to 105 be a very satisfactory wrench as a single notch would be all that would be required for many purposes. A series of notches,

however, make a complete adjustment of wide capacity as indicated. The structure being integral stands heavy strains.

While I have shown a very simple bar 4 for retaining the parts in place other means might be provided.

I therefore desire to claim the invention broadly and also specifically as pointed out in the appended claims.

10 Having thus described my invention what I claim as new and desire to secure by Letters Patent, is:

1. In a pivoted jaw wrench, the combination of a handle with a suitable laterally projecting fixed jaw head integral therewith and serrated on its outer face and having notches on its under side for adjustment and lateral lugs at its projecting extremity, a pivoted jaw slotted to pass over the said handle 15 onto the said jaw head with a pivot at the lower end of the slot to engage the notches successively, and a spring rod pivoted in the lateral projection of said jaw head and adapted to detachably engage a suitable 20 notch for retaining the said pivoted jaw adjustably in position, as specified.

2. In a pivoted jaw wrench, the combination of a handle with a suitable laterally pro-

jecting fixed jaw head integral therewith and serrated on its outer face and having notches on its under side for adjustment and lateral lugs at its projecting extremity, and a pivoted jaw slotted to pass over the said handle onto the said jaw head with a pivot at the lower end of the slot to engage the 30 notches successively.

3. In a pivoted jaw wrench, the combination of a handle with a suitable laterally projecting fixed jaw head integral therewith and serrated on its outer face and having a 35 notch on its under side and lateral lugs at its projecting extremity, and a pivoted jaw slotted to pass over the said handle onto the said jaw head with a pivot at the lower end of the slot to engage the notch.

4. In a wrench, the combination of a suitable handle and laterally projecting fixed jaw head formed integrally together with a serrated jaw face at right angles to said handle, and a pivoted reversible jaw slotted 40 to pivot over the said fixed jaw with a suitable pivoted yieldable retainer to hold the same detachably in place, as specified.

In witness whereof I have hereunto set my hand.

CHARLES J. HARRIS.
